(57) **CLAIM**

The ornamental design for a virtual reality headset power bank as shown and described.

DESCRIPTION

FIG. 1 is a perspective view of a virtual reality headset power bank showing my design;

FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view thereof in a usage state;
FIG. 10 is another perspective view thereof in the usage state;
FIG. 11 is a perspective view of the virtual reality headset power bank shown as a component 1 removed from the assembly in FIGS. 1-8 for clarity of disclosure;
FIG. 12 is another perspective view thereof;
FIG. 13 is a front elevational view thereof;
FIG. 14 is a rear elevational view thereof;
FIG. 15 is a left side elevational view thereof;
FIG. 16 is a right side elevational view thereof;
FIG. 17 is a top plan view thereof;
FIG. 18 is a bottom plan view thereof;
FIG. 19 is an enlarged perspective view of the virtual reality headset power bank shown as a component 2 removed from the assembly in FIGS. 1-8 for clarity of disclosure;
FIG. 20 is another enlarged perspective view thereof;
FIG. 21 is an enlarged front elevational view thereof;
FIG. 22 is an enlarged rear elevational view thereof;
FIG. 23 is an enlarged left side elevational view thereof;
FIG. 24 is an enlarged right side elevational view thereof;
FIG. 25 is an enlarged top plan view thereof; and,
FIG. 26 is an enlarged bottom plan view thereof.
The broken lines in the drawings depict portions of the virtual reality headset power bank that form no part of the claimed design.
